UNITED STATES PATENT OFFICE

AMOS H. PATTERSON AND BUNNIE C. MOOTS, OF BELEN, NEW MEXICO

DRILL PRESS

Application filed October 6, 1926. Serial No. 139,914.

This invention relates to tools, particularly to that type designed for use in boring and drilling holes in various objects or materials, and has for its object the provision of a novel bracket device and other accessories adapted to be used in conjunction with a hand brace of the ordinary type for holding the same securely and properly with respect to the work so that the boring or drilling of holes will be greatly facilitated.

An important object is the provision of a device of this character so constructed and arranged as to clamp or hold an ordinary brace which constitutes the drill proper, means being provided for centering the brace with respect to the work and for effecting feeding thereof to the work.

Another object is to provide a device of this character so constructed and arranged as to hold and utilize a brace regardless of the size thereof, adjustment being provided to take care of variations in size.

A further object is the provision of clamping means for clamping the work upon the base portion of the device and also for effecting clamping of the device itself upon a table, shelf or the like, if such is desired.

An additional object is the provision of a device of this character which will be simple and inexpensive in manufacture, easy to adjust and use, positive in action, efficient and durable in service, and a general improvement in the art.

With the above and other objects and advantages in view, the invention consists in the details of construction, the combination and arrangement of parts to be hereinafter more fully described and claimed and illustrated in the accompanying drawings, in which:—

Figure 1 is a side elevation of one form of the invention.

Figure 2 is a top plan view.

Figure 3 is a front elevation.

Figure 4 is a detail perspective view of the work holding clamp.

Figure 5 is a fragmentary elevation of the upper end of a modified form and

Figure 6 is a plan view thereof.

Referring more particularly to the draw-

ings, the letter A designates, generally, an ordinary brace such as is used by carpenters and other mechanics for boring holes in wood or other materials. Such a brace comprises a crank member B carrying a handle C, the crank member being formed upon a stem D which carries a chuck E for holding the drill or bit F. Carried by the crank B in alignment with the stem D is a knob G which is, under ordinary circumstances, held either against the chest of the operator or in the palm of the hand. The tool is of course of the ratchet type so that the chuck may be rotated in one direction by moving the crank portion back and forth.

In carrying out one form of the invention, we provide a U-shaped bracket 10 adapted to be arranged in a preferably vertical position against a wall or other support indicated at H and secured thereto as by means of bolts 11 or the like. The upper arm 12 of the bracket is apertured as shown for the engagement therein of the lower end of an L-shaped supporting arm 13 held in adjusted position as by means of a pair of nuts 14 screwed thereunto and located at opposite sides of the upper arm 12 of the support or bracket. The horizontal arm of the member 13 is shown as provided with a V-shaped notch 15 and a hook 16, these two elements being provided for the reception of the upper portion of the brace adjacent the knob G.

Threaded through the end portion of the horizontal arm 12 of the bracket is a feed screw 17 having an enlarged operating head 18, this feed screw preferably having a punch point or tapered or conical point adapted to engage within a suitable punch mark or other depression at the upper end of the stem D of the brace for holding the brace centered.

Extending through the lower arm 19 of the bracket is a double ended bolt 20 here shown as held in place by nuts 21 and carrying a clamping plate 22 which is apertured at 23 for the purpose. One end of this clamping plate is provided with a lateral extension 24 bearing upon and rockably engaging the upper surface of the arm 19, the other end of this clamping plate being free and provided with a preferably V-shaped notch 25 to guide

the bit F before and as it passes through the work, the intention being that the work be clamped between the arm 19 and the clamping member 22. The V-shaped notch will have its vertex engaged by the bit which is urged rearwardly and will therefore serve as a guide.

If a wall H or the like is not available against which to secure the bracket or if it is desired to mount the device upon the work itself, use may be made of a clamping plate 26 which is apertured at the proper place and engaged upon the projecting lower end of the double ended bolt 20 and held in place by a nut 27 screwed thereon. The forward end of the plate 26 is angularly inclined as represented at 28 and is adapted to engage against the underside of a shelf, table or other support or against the work, in case such is preferred.

In Figures 5 and 6 we have illustrated a slight modification in which the bracket 29 corresponding to the bracket 10 is not U-shaped but is L-shaped, the vertical arm 30 having slidably mounted thereon the hub 31 of an arm 32 which carries the L-shaped member 13 and also the feed screw 17 in exactly the same manner as above described, the nuts 14 being likewise provided for maintaining the proper adjusted position of the member 13. A set screw 33 or the like is provided for holding the hub 31 of the slideable member in any desired position along the vertical leg or portion 30 of the bracket. In every other respect this form of the invention may be exactly the same as the first described form.

In the operation of either form it will be apparent that the desired drill bit or auger is engaged within the chuck of the brace, the brace is placed in position with the bit engaging against the work held between the clamp 22 and the arm 19, and the feed screw 17 is adjusted to engage the inner or upper end of the stem. The brace is then rotated in the usual manner by grasping the handle 16 and turning the crank back and forth and feeding of the bit to the work is effected by turning the screw 17 either constantly or from time to time as the case may be.

From the foregoing description and a study of the drawings it will be apparent that we have thus provided a very simply constructed, inexpensive and easily installed and used device by means of which an ordinary brace may be used as a drill press either stationarily mounted or capable of being moved about from place to place in accordance with the requirement of the particular work being done. It is really believed that the construction, operation and advantages will be readily apparent to one skilled in the art without further explanation.

While we have shown and described the preferred embodiment of the invention, it should be understood that we reserve the right

to make such changes in the form, construction and arrangement of parts as will not depart from the spirit of the invention or the scope of the subjoined claims.

Having thus described the invention, we claim:

1. A device of the character described comprising a supporting bracket, work clamping means carried thereby, the bracket having a laterally extending arm, a second arm carried by the bracket, above said first named arm, in combination with a ratchet brace carrying a bit adapted to be fed through the work clamping means, the brace having a crank portion, a stem and a knob, the second named arm being formed for embracing engagement with said crank near the knob, and adjustable means carried by the first named arm and abuttingly engaging the stem portion of the brace.

2. A device of the character described comprising a supporting bracket, work clamping means carried thereby, the bracket having a laterally extending arm, a second arm carried by the bracket above said first named arm, in combination with a ratchet brace carrying a bit adapted to be fed through the work clamping means, the brace having a crank portion, a stem and a knob, the second named arm being formed for embracing engagement with said crank near the knob, means carried by the first named arm and engaging the stem portion of the brace, and means for adjusting the second named arm with respect to the first named arm.

3. A device of the character described comprising a supporting bracket, work clamping means carried thereby, the bracket having a laterally extending arm, a second arm carried by the bracket above said first named arm, in combination with a ratchet brace carrying a bit adapted to be fed through the work clamping means, the brace having a crank portion, a stem and a knob, the second arm being formed for embracing engagement with said crank near the knob, means carried by the first named arm and engaging the stem portion of the brace, and means for adjusting the second named arm with respect to the first named arm, the first named arm being bodily adjustably mounted with respect to the bracket.

4. A device of the character described comprising a supporting bracket including a vertical arm and a lower horizontal arm, an upper horizontal arm carried by the vertical arm of the bracket, a work clamping member mounted above the lower horizontal arm, a support engaging clamp mounted beneath the lower horizontal arm, screw means carried by the first named arm and adjustably connected with said work holding means for adjusting the position thereof in clamping relation to the work, one of said work holding clamping means acting as a guide for the

bit of a brace, the brace including a crank portion and being adapted for location within the bracket with the crank portion opposite the upper end portion of the bracket, a screw adjustably mounted on the second named arm and engageable with the stem of the brace axially thereof and in alinement with the bit, and an additional arm adjustably mounted upon the upper horizontal arm and adapted to embracingly engage the brace near the handle portion thereof.

In testimony whereof we affix our signatures.

BUNNIE C. MOOTS.
AMOS H. PATTERSON.
